RECAPITULATOR BOARD

Walter O. Critchfield, Shelby, Ohio, assignor to
 Shelby Salesbook Company, Shelby, Ohio, a
 corporation of Ohio

Application April 25, 1941, Serial No. 390,403

4 Claims. (Cl. 281—44)

My invention relates to the disposition and handling of record sheets, and has among its objects and advantages the provision of an improved recapitulator board.

An object of my invention is to provide a recapitulator board devised to effectively handle a large number of record sheets and the like, wherein the device embodies novel means for supporting the sheets in a neat and orderly shingled relationship, and in which the sheets may be so arranged and supported as to be individually and readily accessible for inspection of subject matter other than that which is normally exposed by reason of the shingle-like arrangement of the sheets.

A further object is to provide a device of the type set forth in which a large number of record sheets may be effectively supported in shingle-like relationship, in which novel clamps are provided for securing the sheets against accidental displacement, and in which the clamps are so devised as to be readily shifted to inoperative positions so that all the sheets may be quickly and easily assembled in a stack by one sweep of the hand.

Another object is to provide a recapitulator board having means for supporting and aligning a relatively large number of record sheets in shingle formation, wherein the board incorporates guide means as an aid in aligning the sheets relatively one to the other so as to provide an orderly arrangement thereof, and in which the board is provided with guide means facilitating placement of the record sheets when starting the shingled arrangement thereof from either end of the board.

In the accompanying drawings:

Figure 1 is a plan view of my invention illustrating record sheets placed thereon in shingle relationship;

Figure 2 is a side view;

Figure 3 is a view taken substantially along the line 3—3 of Figure 1; and

Figure 4 is a view of the structure of Figure 3 but illustrating one of the sheet holding clamps in its inoperative position, in contradistinction to the holding position of the clamp in Figure 3.

In the embodiment selected for illustration, the board 10 comprises a panel 12 upon which the record sheets 14 are arranged in shingled relationship. To the bottom face of the panel 10 is secured a frame 16 which has a slight taper, as illustrated in Figures 3 and 4, so as to hold the panel at a slight angle to the horizontal which facilitates work on or inspection of the

record sheets 14. In devices constructed of lumber, the frame 16 may be glued to the panel 12 and the panel 12 preferably comprises plywood to prevent warping thereof.

Along one side of the board 10 and on the upper edge margin of the panel 12 is secured a plurality of bars 18 in end to end alignment but spaced to provide accommodation for a plurality of sheet clamps 20. An adjustable guide strip 22 extends along the opposite side margin of the panel, the guide strip and the bars 18 being arranged in parallelism but spaced so that the record sheets 14 may pass freely therebetween to rest on the panel 12. Slots 24 are provided in the guide strip 22 for the reception of screws 26 threaded into the panel 12 and the frame 16. Thus, the guide strip may be adjusted to different positions and made secure by merely tightening the screws 26.

20 The two runs 28 of the frame 16 are sufficiently wide to extend slightly above the upper face of the panel 12 for sheet guiding purposes. Each run is recessed at 30 centrally of the panel and to a depth flush with the upper face of the panel.

25 Thus, the margins of the runs 28 extending above the panel 12 provide sheet guides whereby the sheets 14 may be laid in shingled relationship from either end of the board, depending upon the personal desires of the user. The guide strip 22 and the bars 18 function to guide the record sheets with respect to transverse misplacement and enable the user to lay and space the sheets in an expeditious manner.

30 35 All the clamps 20 are identical in construction and operation. Figure 1 illustrates three of the clamps 20 as underlying certain of the record sheets 14. This is permitted by reason of the fact that the clamps are formed of relatively thin strip material. The record sheets are arranged with a slight exposure, such as one-quarter inch in contradistinction to the usual three-quarter to one inch exposure.

40 45 50 While the record sheets may be arranged with slight exposure, it is a relatively easy matter to raise predetermined sheets for completely exposing figures on other sheets. All the sheets lie in an orderly arrangement and the thin formation of the clamp which might underlie certain sheets eliminates bulk formations thereabout. All the clamps are spring tensioned so as to effectively clamp the sheets to the panel 12. The clamps are also mounted for pivotal movement so as to move clear of the sheets and sufficiently far from the panel 12 to permit the sheets to be picked up by one sweep of the hand.

The cutouts 30 permit either hand to sweep the record sheets off the panel, depending upon the direction in which the sheets are laid in shingled relationship.

Each of the clamps 20 is bent to provide an ear 32 fixedly secured to a block 34 by screws 36. Each block 34 is positioned between two spaced brackets 38 and is pivotally secured thereto by reason of a bolt 40, the brackets being secured to the frame 16 by screws 42.

Referring to Figures 3 and 4, the block 34 illustrated therein is provided with a pin 44 which may be threaded into the block and is arranged at right angles to the clamp 20. It will be noted that the clamp 20 parallels the panel 12 and that the bars 18 are spaced so as to permit the clamps to pivot without obstruction therefrom. In Figures 3 and 4 a plate 46 is spring urged against the block 34, the spring 48 being arranged with one end engaging the plate 46 and its other end resting in a shallow depression 50 in the frame 16. Two screws 52 are threaded into the frame 16 and pass loosely through openings in the plate 46. All the blocks 34 are of like construction and are preferably of rectangular contour when viewed from the end so as to provide faces engageable by the respective plates 46, in addition to having faces for mounting of the ears 32.

Figure 4 illustrates the clamp 20 in its raised or inoperative position. The plate 46 is pressed firmly against the face 54 of the block 34 to firmly support the latter against pivotal movement. The plate may shift and pivot freely relatively to the screws 52 because of the loose fit of the screws in the openings in the plate. At the same time, the screws support the plate 54 in proper assembly with respect to its cooperating parts. In pivoting the clamp 20 in a counterclockwise direction, as in Figure 4, the corner 56 of the block 34 slides on the plate 46 and as the block 34 is rotated sufficiently far to bring the corner 56 beyond dead center, the spring 48 presses the plate 46 against the block with a sufficient force to pivot the clamp with a snap action. In the normal clamping position of the clamp 20, the plate 46 presses firmly against the face 58 of the block 34 so that the block is firmly but yieldingly supported in either of its two positions. Pivotal movement of the clamp 20 is facilitated by reason of the pin 44.

Without further elaboration, the foregoing will so fully illustrate my invention, that others may, by applying current knowledge, readily adapt the same for use under various conditions of service.

I claim:

1. A board of the type described comprising a panel for supporting record sheets in shingled relationship, guide means on said panel for the top ends of the record sheets, said guide means extending above the sheet supporting face of said panel and having openings therein, pivotally

and resiliently urged clamps mounted on said panel for holding the record sheets thereagainst, with the clamps pivoting in said openings, means for yieldingly supporting the clamps against accidental pivotal movement in its respective operative and inoperative positions, and guides at opposite ends of said panel for respectively guiding the initial end record sheets in the shingled relationship thereof when arranged from either end of the panel, the guides at the ends of said panel being cut away flush with the sheet supporting face of the panel.

2. A board of the type described comprising a panel for supporting sheets in shingled relationship, clamps for holding the sheets against the panel, each clamp comprising a flat finger arranged to press against the sheets, a bracket secured to the panel, a body fixedly secured to the finger and rotatably mounted on the bracket, said body having flat faces, resilient means selectively acting on said flat faces in the operative and inoperative positions of the finger, said resilient means comprising a plate mounted for limited free movement, and a spring interposed between the panel and the plate for urging the latter against said body.

3. A board of the type described comprising a panel for supporting sheets in shingled relationship, clamps for holding the sheets against the panel, each clamp comprising a flat finger arranged to press against the sheets, a bracket secured to the panel, a body fixedly secured to the finger and rotatably mounted on the bracket, said body having flat faces, resilient means selectively acting on said flat faces in the operative and inoperative positions of the finger, said resilient means comprising a plate mounted for limited free movement, a spring interposed between the panel and the plate for urging the latter against said body, and a pin-like grip secured to the body.

4. A board of the type described comprising a panel for supporting sheets in shingled relationship, clamps for holding the sheets against the panel, each clamp comprising a flat finger arranged to press against the sheets, a bracket secured to the panel, a body fixedly secured to the finger and rotatably mounted on the bracket, said body having flat faces, resilient means selectively acting on said flat faces in the operative and inoperative positions of the finger, said resilient means comprising a plate mounted for limited free movement, a spring interposed between the panel and the plate for urging the latter against said body, and a pin-like grip secured to the body, all said fingers normally paralleling the supporting face of said panel when brought into engagement with the sheets, but pivotally movable to positions substantially at right angles to said face.

WALTER O. CRITCHFIELD.
